(57) **CLAIM**

The ornamental design for hand operated agricultural atomizer, as shown and described.

DESCRIPTION

2.-3. Hand operated agricultural atomizer
2.1 is a top view of an hand operated agricultural atomizer, showing our new design;
2.2 is a front view thereof;
2.3 is a right side view thereof;
2.4 is a bottom view thereof;
2.5 is a rear right perspective thereof;
2.6 is a rear view thereof;
2.7 is a rear left perspective thereof;
2.8 is a bottom left perspective view thereof;
3.1 is a top view of an hand operated agricultural atomizer, showing our new design;
3.2 is rear left perspective view thereof;
3.3 is a right side view thereof;
3.4 is a bottom view thereof;
3.5 is a front view thereof;
3.6 is a rear right perspective view thereof;
3.7 is a bottom left perspective thereof;
3.8 is a rear view.
